MAGNETIC TAPE TRANSPORT

Glenn A. Smith, Redwood City, Calif., assignor to Am-
pex Corporation, Redwood City, Calif., a corporation
of California

Filed Sept. 9, 1963, Ser. No. 76,526

Term of patent 14 years

(Cl. D26—5)

FIG. 1

Des. 200,576

PAGE 2

FIG. 2

Des. 200,576

PAGE 3

FIG. 3

Des. 200,576

PAGE 4

FIG. 4

FIG. 5

FIG. 1 is a side, top and front perspective view of a magnetic tape transport, showing my new design;

FIG. 2 is a top and front perspective view;

FIG. 3 is a side elevational view, the opposite side being substantially a mirror image thereof;

FIG. 4 is a rear perspective view thereof; and

FIG. 5 is a top plan view thereof.

Portions of the drawing figures are diagonally lined to indicate transparency.

I claim:

The ornamental design for a magnetic tape transport, substantially as shown and described.
